METHOD AND APPARATUS FOR RADIO RECEPTION.

Application filed February 19, 1924. Serial No. 693,747.

This invention relates to a method and apparatus for the translation and amplification of modulated currents, particularly high frequency oscillating currents modulated at an audio frequency, such as voice frequency in the case of telephony. More specifically, this invention relates to a method and apparatus for translating with amplification of alternating currents such as are set up in the collectors of radio receiving stations.

One of the objects of this invention is to provide a simple, practical and thoroughly reliable apparatus for detecting or translating modulated currents, particularly such modulated currents as are characteristic, for example, in the art of transmitting intelligence or subject by radio. Another object of this invention is to provide a simple and compact apparatus for translating with amplification modulated currents, and to provide apparatus of the above-mentioned character which will be of efficient action, easy of control, simple and convenient manipulation, and ready adjustability. Another object of this invention is to provide apparatus of the above-mentioned nature which will be not only of compact construction, but also of inexpensive manufacture, all without departing from high efficiency, reliability and dependability of action when in use. Another object of this invention is to provide apparatus of the above nature which will be well adapted to meet the conditions of hard practical use and which may be controlled, manipulated or operated with the requirement of a minimum amount of skill. Another object of this invention is to provide a thoroughly practical art of detecting, translating, or amplifying modulated currents and one which may be in practice readily and inexpensively carried on. Other objects will be in part obvious or in part pointed out hereinafter.

The invention accordingly consists in the features of construction, combinations of elements, arrangements of parts and in the several steps and relation and order of each of the same to one or more of the others all as will be illustratively described herein, and the scope of the application of which will be indicated in the following claims.

In the accompanying drawing in which are shown several of various possible embodiments of the mechanical features of this invention,

Figure 1 is a schematic diagram of the circuit connections certain of the mechanical features of the invention being shown in detail and on an enlarged scale in vertical central section;

Figure 2 is a fragmentary sectional view on an enlarged scale showing certain preferred details of mechanical construction of part of the apparatus shown in Figure 1.

Figure 3 is a view similar to that of Figure 2, but showing a modified form.

Figure 4 is a detailed fragmentary view of a part of the apparatus shown in Figure 1, and it is a fragmentary view as seen from the right of Figure 1.

Similar reference characters refer to similar parts throughout the several views of the drawing.

Referring now to the drawing and more particularly to Figure 1, there is shown at 10 a collector, conveniently taking the form to an antenna connected through a variable inductance 11 to ground 12, the variable inductance 11 permitting the collector circuit to be tuned to any desired frequency or wave length. A secondary circuit, preferably also tunable or adjustable at will to the desired wave length or frequency, comprises preferably a variable inductance 13, which, with the variable inductance 11, may conveniently form the coupling between the collector circuit and the secondary circuit, a condenser 14, which may be fixed, and a condenser 15, preferably variable. The coupling between the coils 11 and 13 is preferably made variable at will.

The secondary circuit 13—14—15 may thus be adjusted to the desired frequency or wave length of the modulated oscillating current, the energy of which is illustratively shown as being transmitted by radio and hence received by the collector 10 and associated primary tuning circuit, but it is to be understood that the energy of the modulated oscillating current may be transmitted in any other convenient or suitable manner and suitably transferred to the secondary receiving circuit.

A ring-shaped member 16, preferably made of a suitable insulating material, and held in rigid position in any suitable manner, supports rigidly therein a coil 17, preferably of the pancake type, and having a suitable number of turns and preferably several layers of turns of wire therein. In

Figure 1 there are illustratively shown four layers of turns of wire in this coil 17. To the right of the coil 17 and spaced therefrom is a coil 18, also preferably of the pancake type, having a suitable number of turns therein and illustratively shown in Figure 1 as comprising only a single layer of turns. The wire of the coil 18 is preferably made of a light metal, so as to maintain the mass of the coil 18 at a minimum and is supported by and attached in any suitable manner to a movable member 19 taking the form preferably of a metallic, and hence conductive, plate member, it being understood that the several turns of wire in the coil 18 are insulated one from the other and insulated also from the plate member 19. The plate member 19, moreover, is also preferably made of a light material, so that the mass thereof is maintained at a minimum, and the plate member 19 furthermore is preferably so formed and of such material as to have good vibrating or sound reproducing characteristics.

Considering now the mounting of the plate member 19, it is to be noted first that the plate member 19 with the coil 18 thereon are preferably of disk-like shape, and the outer periphery of the disk plate member 19 is supported in a ring member 20, preferably of insulating material, such as fiber or bakelite, for example. The ring member 20 is extended to the left as seen in Figure 1 and at this extended portion is threaded interiorly as at 20^a. The threaded portion 20^a is in threaded engagement with the exteriorly threaded portion 16^a of the ring member 16 which rigidly supports the coil 17. At this point it may be noted that the inter-threaded relation between the supporting ring members 16 and 20 permit not only a rapid and convenient assembly of the parts and inexpensive manufacture, but also permit of a rapid and at the same time precise positioning or adjusting of the coil 18 with respect to the coil 17, in order that the action therebetween, to be more clearly hereafter described, may be made most efficient for given conditions of operation.

Spaced from the plate member 19 and to the right thereof, as viewed in Figure 1, is mounted a plate member 21, preferably metallic throughout, and hence conductive, and having a thickness or other appropriate characteristics as to give the plate member 21 a substantial rigidity or freedom from distortion. The plate member 21 is supported preferably throughout its periphery by another ring member 22, preferably of a suitable insulating or non-conducting material and is rigidly secured thereto. The ring member 22, however, is extended toward the left, as viewed in Figure 1 and at this extended portion is interiorly threaded, as at 22^a, in order to be received and threaded upon the exteriorly threaded portion 20^b of the ring

member 20. As hereinbefore noted in connection with the relation between the ring members 20 and 16, it may also, at this point, be pointed out that the threaded relation between the ring member 22 which supports the plate member 21, and the ring member 20 which supports the plate member 19 likewise permits of a rapid, but at the same time precise positioning of the plate member 21 with respect to the plate member 19. Moreover, it will be noted that all of the several parts are rigidly held in assembled position or relation and that by rotating either of the ring members 20 or 22 in either direction, the threaded relation between these several parts permits the ready adjustment of the several parts for most efficient action for given conditions.

The plate member 21, like the plate member 19, is also preferably disk-like in shape and the plate members 19 and 21 are preferably of such diameters or dimensions as to present adjacent surfaces of substantially equal area. The plate member 21, however, is provided at its central portion with an opening 21^a of suitable area and attached to the disk member 21 and in substantial registry with the opening 21^a is a suitable sound box or sound projector 23.

The coils 17 and 18 are connected preferably in series with each other as by the flexible connection or conductor 24 and by means of the conductors 25 and 26 are connected to the receiving circuit, preferably as by projecting these two coils in series across the condenser 15. The coils 17 and 18 may thus be energized by modulated current, and as illustratively shown in Figure 1 and illustratively hereinabove described, will be responsive to a high frequency oscillating current modulated in accordance with an audio frequency, such as, for example, voice frequency. The interaction between the fixed coils 17 and the movable coil 18 will thus vary in accordance with the amplitude in substantial accordance with the amplitude of the modulated current, but where this current is of high frequency, the inertia of the movable coil 18 and disk

or diaphragm 19, will be such as to prevent these parts from vibrating at the high or carrier frequency. The movable parts, however, will partake of a vibrating motion commensurate with the envelope of the modulated high frequency current, and where this envelope represents a voice frequency, the vibrations of the diaphragm 19 will reproduce the corresponding voice frequency and hence sound. As the diaphragm 19 vibrates thus at substantially the frequency of modulation, it will be noted that the spacing between the plate member 19 and the relatively fixed plate member 21 varies at a corresponding rate, namely at the frequency of modulation.

The plate members 19 and 21 form a con-

denser, the capacity of which varies with the spacing between the two plate members. The condenser thus formed by the plates 19 and 21 is included in a circuit having therein a 5 source of current 27 of suitable potential, the flow of current from which is governed by the variation in the capacity between the plates 19 and 21. Thus a conductor 28 connects the source 27 to one plate (21) of this 10 condenser, a conductor 29 connects the other plate (19) of this condenser to the other side of the source 27 but through the primary winding 30 of a transformer 30—31 and through an adjustable resistance 32. The 15 secondary winding 31 of the transformer 30—31 is substantially bridged across the coils 17 and 18, and in Figure 1 is shown connected to or bridged across these coils through the inductance 13. The transformer 20 30—31 preferably contains an iron core not only to prevent the passage through the secondary winding 31 of the high frequency modulated current, which is by-passed through the condenser 14, but also to insure 25 an efficient transformation of the direct current from the auxiliary source 27, varying at the frequency of modulation, into an alternating current of commensurate frequency for direct action upon the diaphragm moving 30 coils 17 and 18. Thus, as the diaphragm 19 vibrates and hence varies the spacing between the condenser plates 19 and 21, the leakage current flowing between these two plates and hence through the primary winding 30 of 35 the transformer 30—31 partakes of variations commensurate with the rate or frequency of vibration of the diaphragm 19. The energy thus variably controlled from the auxiliary source, illustratively shown as being 40 a direct current source, is thus made to supplement the initial energy received from the collector or other transmitting circuit and is effective to cause the initial vibration of the diaphragm 19. The vibration of the latter 45 is thus materially reenforced or enhanced, and the corresponding sound waves materially increased and amplified, these sound waves being projected through the sound box 23.

It may be pointed out that the several 50 parts, such as the coils and plate members, each preferably disk-like in shape or form, are, by the construction hereinbefore described, effectively held in substantially parallel relation with respect to one another and that this parallel relation is maintained irrespective of the adjustments that may be given one of the parts with respect to the other. The diaphragm 19 may vibrate as by 55 deflections, but it is preferably arranged to 60 vibrate also bodily toward or away from the relatively fixed plate member 21. Thus, referring still to Figure 1 the ring member 20 is provided with an annular groove or recess 20^c between the spaced side walls of which 65 is received the diaphragm 19, but between

which and the diaphragm are interposed the resilient or yielding supporting rings 20^a and 20^e, one on each side of the diaphragm 19. These supporting rings are preferably of readily yieldable rubber, and are tapered 70 toward the diaphragm as is clearly shown in Figure 1 in order to permit a ready vibrating movement bodily of the diaphragm 19 in a direction substantially transverse to its own plane. The plate member 19 may thus be 75 held substantially parallel to itself and to the cooperating plate member 21, throughout its vibratory movements, and by this arrangement there is achieved not only a highly effective vibration of the intervening ether 80 or atmosphere, thereby to set up effectively corresponding sound waves, but also an efficient variation in the capacity between the two plates 19 and 21. It is to be understood, however, that the sound waves may be set up 85 or produced by the vibrating diaphragm 19 not only by the bodily or piston-like vibrations thereof, but also by such inherent vibrations of the diaphragm as may be characterized by deflections of the diaphragm 19, or 90 both; and it is pointed out furthermore that the term "vibration" or "vibrating" is herein intended to be used broadly to comprehend either or both of these above-mentioned 95 sound producing movements in or of the diaphragm 19.

From the foregoing it is believed that the 100 operation of the apparatus will be clearly understood; it may be pointed out, however, that I prefer to make the apparatus more sensitive in its control of the energy from the auxiliary source and for this purpose I may adopt an arrangement illustratively shown in Figure 2. In this figure there is 105 shown an enlarged scale a fragmentary portion of the vibrating diaphragm 19 with the coil 18 associated therewith, and the fixed plate member designated at 21^a. One of these plate members, such as and preferably the stationary or fixed plate member 21^a I 110 provide with a series of projecting points 21^b on that face of the plate which is adjacent the cooperating plate member. These points 21^b may be of any suitable number and are 115 preferably not only of substantially uniform length, but also of substantially uniform distribution throughout the face of the plate member 21^a. These points 21^b greatly facilitate the flow of the displacement current 120 from one plate to the other, and may be considered as permitting the flow of current between the two plates to partake of the nature of a brush discharge.

I may, however, also substantially concentrate or restrict the path of flow of the condenser leakage current by substantially concentrating the projections on one of the plates, and thus for example, I may utilize the arrangement shown in Figure 3, in which one of the plate members, such as the station- 130

ary plate member designated as 21^e is provided at a central portion thereof and substantially about the central opening 21^a therein with a ring or annulus 21^f, preferably 5 integrally formed with the plate member and presenting a sharp ring-shaped edge projecting toward the other plate. This projecting ring-shaped edge may thus act 10 to facilitate the passage of the leakage current from one plate to the other and this may take place even also in the form of a brush discharge. This latter arrangement, shown 15 in Figure 3, is particularly advantageous where the sound producing member partakes 20 of deflections or distortions as it vibrates, it being understood that, where the vibrating member is disk-like in shape, such deflectional vibrations thereof are most effective or have their greatest amplitude at the center 25 of the diaphragm, and that in relating the projecting member, such as the ring-shaped member 21^f, in the region where the amplitude of the movable member is a maximum there is achieved not only a rapid or quickly responsive action, but also a greater 30 intensity of flow in the displacement or leakage current.

It will thus be seen that the leakage current may be greatly intensified and that the 35 action of the transformer 30—31, forming an inductive coupling between the receiving circuit and the circuit of the auxiliary source, as illustrative of a possible form of coupling that may be employed, is made highly effective in transferring a large amount of energy from the latter circuit to the diaphragm moving coil or coils.

As hereinbefore noted, the coils 18 and 17 40 may be adjusted relatively one to the other in order to achieve the most efficient interaction therebetween for given conditions. These coils, it may be noted, are preferably so related to each other electrically as to oppose each other in order that an increase, for 45 example, in intensity of the current of one coil will cause a repulsion of the other coil, and hence move the diaphragm 19 toward the fixed plate member 21. The fixed distance or space between the plate members 19 and 21 50 is also adjustable, as hereinbefore noted, and it may here be pointed out that this adjustment provides a convenient means for adjusting the condenser to the potential of the auxiliary source, illustratively shown as a direct 55 current source in the form of a battery 27; moreover, this adjustment of the spacing between the plate members 19 and 21 permits an exact predetermination to be made commensurate with the potential of the auxiliary 60 source so as to maintain the energy transfer between the two plates in a form of a leakage current or even a brush discharge, but to prevent a disruptive discharge. In this connection also it may be noted that the variable 65 resistance 32 forms a convenient adjustable

balancing resistance to prevent disrupted discharges, it being noted that a disrupted discharge is in general preceded by a brush discharge and that the flow of the current corresponding to this brush discharge insures a slight voltage drop in the ballast resistance 70 32. There is thus insured a slight drop in potential between the two plates and the transition from a brush discharge to disrupted discharge is thus effectively avoided or prevented. 75

Each of the ring members 20 and 22 is split radially at a convenient point in the circumference thereof in order to permit the ring members, after relative adjustment, to be 80 clamped upon their coacting threaded members, thus to lock the parts in adjusted position. In Figure 4 is shown fragmentarily one of these ring members such as the ring member 22 provided with a cut or slit 22^b, and 85 with the outwardly projecting shoulders 22^c and 22^d, adapted to be drawn together as by the clamping screw 22^e threaded into one of them and adapted to permit a contraction of the ring member to clamp it into place. 90

From the foregoing, the manner of practicing my invention will be clear; as conducive, however, to a possible clearer understanding of certain actions that take place, certain theoretical considerations might be set forth. The capacity C of a condenser is the quotient of the numerical value of the charge Q on either conductor or plate of the condenser by the difference of potential V between the two conductors when equal and opposite charges are given the conductors, i. e., $C=Q/V$. From this relation it follows that the potential difference V across the two conductors becomes Q/C . The condenser formed by the plates 19 and 21 of the apparatus hereinabove described, having been initially charged, a subsequent movement of one of the plates or diaphragms with respect to the other changes the capacity C so that there is brought about a change in the potential difference between the plates 19 and 21, as will be seen from the relation $V=Q/C$. Depending upon whether the resultant potential difference between the plates 19 and 21 is thus made greater or less than the voltage of the 100 source of potential 27, there results in the corresponding circuit a flow of current varying in one direction or the other, and through the primary winding 30 of the transformer 30—31. The reaction of the current in the 105 primary winding 30 upon the secondary winding 31 and of the latter upon the remaining portions of the circuit will be clear from what has hereinbefore been set forth in detail. It may further be pointed out that in any condenser, where the strength of the dielectric field between the two plates is varied or changed, there takes place a loss of energy in the dielectric. This phenomena is analogous 110 to magnetic hysteresis and the losses thus generated 115

erated are, of course, supplied from the source energizing the condenser. While such a loss is ordinarily present and recognized where the change in the dielectric field of a condenser takes place due to changes in the potential applied to the two plates thereof, yet in the apparatus hereinabove described the change in the dielectric field is brought about by the continuous change in the relative position of the plates 19 and 21, in turn brought about by the vibration in audio frequency of the one with respect to the other. Such a variation in the dielectric field at an audio frequency rate causes the dissipation of energy in the dielectric field and the corresponding loss is supplied by a current flow from the source of potential 27, and hence through the primary winding 30 of the transformer 30—31. This latter current from the source 27 which supplies the losses just mentioned may supplement the action immediately above described according to which, as above noted, the changes in the capacity C, due to the vibration of the one plate with respect to the other, cause a varying current flow through the primary winding 30 of the transformer.

It will thus be seen that there has been provided in this invention a simple and thoroughly practical method and apparatus for translating and amplifying modulated currents. It will furthermore be noted that the apparatus is of simple and compact construction, of simple manipulation and adjustment and of thoroughly reliable and dependable action throughout. It will also be noted that the method provided by this invention may furthermore be readily and inexpensively carried out in practice and with highly efficient and dependable results. It will also be seen that the several objects of this invention, together with many advantages are successfully achieved.

As many possible embodiments might be made of the mechanical features of the above invention and as the method herein described might be varied in various particulars, all without departing from the scope of the invention, it is to be understood that all matter described herein and shown in the accompanying drawing is to be interpreted as illustrative and not in a limiting sense.

I claim as my invention:

1. The herein described art which consists in utilizing the energy of a high frequency oscillating current modulated at audio frequency to produce motion in a member at substantially the audio frequency rate, utilizing the motion of said member to cause a current flow varying in intensity substantially at the said audio frequency rate, and utilizing said variable current flow to increase the amplitude of the motion in said member.

2. The herein described art which consists in utilizing the energy of the high frequency current to vary the distance between two

spaced conductive members at the frequency of modulation, utilizing the variation in spacing between said two conductive members to vary the displacement current flow therebetween and from an auxiliary source, 70 and in supplementing the energy of the modulated high frequency current with energy from said auxiliary source proportional to the said variable displacement current.

3. The herein described art which consists 75 in utilizing opposed magnetic effects of the modulated current to produce motion in a member, utilizing the motion of said member to control the flow of energy from an auxiliary source, and in supplementing said opposed magnetic effects of the modulated current with opposed magnetic effects of the controlled current from said auxiliary source.

4. The herein described art which consists 85 in utilizing opposed magnetic effects of the modulated current to produce motion in a member at the frequency of modulation, utilizing the motion of said member to produce from an auxiliary source a current of the frequency of modulation, and in superimposing 90 the energy of the current from said auxiliary source upon said modulated current to increase the amplitude of motion in said member.

5. The herein described art which consists 95 in utilizing opposed magnetic effects of the modulated current to produce motion in a member at the frequency of modulation, utilizing the motion of said member to produce from an auxiliary source a current of the frequency of modulation, and in utilizing the energy of the current from said auxiliary source superimposed upon the modulated current to produce opposed magnetic effects of the current from said auxiliary source to 100 increase the amplitude of motion in said member.

6. The herein described art which consists in utilizing the energy of the modulated current to vibrate a sound reproducing member, 110 utilizing the motion of the said sound reproducing member to control the flow of energy from an auxiliary source at a variable rate corresponding substantially to the vibration of said member, and in superimposing the energy of the modulated current upon the energy from said auxiliary source to vibrate said member.

7. The herein described art which consists in causing the energy of a modulated current 120 to vibrate a conductive sound reproducing member and to vary the spacing thereof from a relatively fixed conductive member, each at substantially the frequency of modulation, utilizing the variation in spacing between 125 two said conductive members to vary the displacement current flowing therebetween and from an auxiliary source, and in utilizing energy from said auxiliary source and proportional to said displacement current to affect 130

the vibration of said sound reproducing member.

8. In apparatus of the character described, in combination, a diaphragm, a coil mounted to move with said diaphragm, electromagnetic means coacting with said coil to cause vibrations of said diaphragm, an auxiliary source of current, means responsive to the vibrations of said diaphragm for causing 10 variations in the flow of current from said auxiliary source, and means for energizing said electromagnetic means by energy derived from said auxiliary source.

9. In apparatus of the character described, 15 in combination, a pair of spaced conductive members, adapted to form a capacity, one of which members is movable relative to the other, means responsive to a modulated current for moving one of said members with respect to the other, a local circuit including 20 an auxiliary source of current and said two spaced members, and means for affecting the movement of said movable member and responsive to the flow of current in said local 25 circuit.

10. In apparatus of the character described, in combination, a pair of spaced conductive members adapted to form a capacity, one of which members is movable with respect to the other, means responsive to a modulated current for vibrating one of said 30 members at substantially the frequency of modulation, electromagnetic means for affecting the vibration of said movable member and including an auxiliary source of current, the current output of which is controlled by the variation in the capacity between said two spaced members.

11. In apparatus of the character described, 40 in combination, a receiving circuit adapted to be responsive to a modulated high frequency oscillating current, a movable member, electromagnetic means adapted to be energized from said receiving circuit and adapted to affect said movable member to vibrate at substantially the frequency of modulation of said 45 oscillating current, an auxiliary source of current, and means responsive to the vibrations of said movable member and adapted to cause variations in the flow of current from 50 said auxiliary source at a rate substantially equivalent to the frequency of modulation of said oscillating current, said electromagnetic means being responsive to the varying current 55 from said auxiliary source, thereby to reinforce the vibrations of said movable member.

12. In apparatus of the character described, 60 in combination, a diaphragm, means responsive to a modulated high frequency oscillating current for vibrating said diaphragm at a rate substantially equivalent to the frequency of modulation of said oscillating current, a relatively fixed member arranged in spaced relation from said diaphragm and 65 adapted to form therewith a capacity, an

auxiliary source of current having included in the circuit thereof the capacity formed by said two members, and means responsive to the flow of current between said two spaced members for affecting the vibration of said 70 diaphragm.

13. In apparatus of the character described, in combination, a movable conductive plate member, electromagnetic means adapted to be responsive to a modulated high frequency oscillating current for vibrating said plate member at a rate substantially equivalent to the frequency of modulation of said oscillating current and adapted also to be responsive to a current of frequency commensurate with the frequency of modulation, a relatively fixed plate member arranged in spaced relation from said first-mentioned plate member and adapted to form therewith a capacity, an auxiliary source of current having included in the circuit thereof the capacity formed by said two plate members, and means for energizing said electromagnetic means with energy from said auxiliary 90 source.

14. In apparatus of the character described, in combination, a movable member, electromagnetic means for vibrating said member and adapted to be responsive to a modulated high frequency oscillating current and also 95 to a low frequency alternating current, an auxiliary source of direct current, means responsive to the vibrations of said member for causing variations in the flow of current from said auxiliary source at a rate substantially commensurate with the frequency of modulation of said oscillating current, means for converting said varying direct current from said auxiliary source into a low frequency alternating current, and means for energizing said electromagnetic means with said 100 low frequency alternating current.

15. In apparatus of the character described, in combination, a movable plate member, electromagnetic means for vibrating said 110 plate member and adapted to be responsive both to a modulated high frequency oscillating current and a current of a frequency commensurate with the frequency of modulation of said oscillating current, a relatively fixed plate member arranged in spaced relation relative to said movable member and adapted to form therewith a capacity, an auxiliary source of direct current having included in the circuit thereof a capacity formed by said 115 two plate members, whereby the flow of current from said auxiliary source is made to vary at a rate substantially equivalent to the frequency of modulation of said high frequency current, means for converting the 120 variable direct current from said auxiliary source into an alternating current, and means for energizing said electromagnetic means with the derived alternating current.

16. In apparatus of the character de- 130

- scribed, in combination, a pair of spaced conductive members adapted to form a capacity, one of which members is movable with respect to the other to vary the capacity of said two members, means responsive to a modulated current for vibrating said movable member, thereby to vary the capacity between said two members at substantially the frequency of modulation of said current, an auxiliary source of current having included in the circuit thereof the capacity formed by said two members, and means responsive to the flow of current from said auxiliary source for affecting the vibration of said movable member, and means for adjusting the spacing between said two members. 10
17. In apparatus of the character described, in combination, a pair of spaced conductive members adapted to form a capacity, one of which members is movable with respect to the other to vary the capacity of said two members, means mounting said movable member with respect to the other to permit bodily movement thereof toward or away 20 from the other, means responsive to a modulated current for bodily vibrating said movable member at a rate substantially equivalent to the frequency of modulation of said current, an auxiliary source of current having included in the circuit thereof the capacity formed by said two members, and means responsive to the flow of current from said auxiliary source and through said capacity for affecting the vibration of said movable member. 30
18. In apparatus of the character described, in combination, a pair of spaced conductive members adapted to form a capacity, one of which members is movable with respect to the other to vary the capacity of said two members, means mounting said movable member with respect to the other to permit bodily movement thereof toward or away from the other, means responsive to a modulated current for bodily vibrating said movable member at a rate substantially equivalent to the frequency of modulation of said current, an auxiliary source of current having included in the circuit thereof the capacity formed by said two members, and means responsive to the flow of current from said auxiliary source and through said capacity for affecting the vibration of said movable member, and means for adjusting the spacing between said two members. 40
19. In apparatus of the character described, in combination, a pair of spaced conductive members adapted to form a capacity, one of which members is movable with respect to the other to vary the capacity of said two members, means mounting said movable member with respect to the other to permit bodily movement thereof toward or away from the other, means responsive to a modulated current for bodily vibrating said mov- 50
- able member at a rate substantially equivalent to the frequency of modulation of said current, an auxiliary source of current having included in the circuit thereof the capacity formed by said two members, and means responsive to the flow of current from said auxiliary source and through said capacity for affecting the vibration of said movable member, and means for facilitating the flow of leakage current from one of said members to the other. 70
20. In apparatus of the character described, in combination, a pair of spaced conductive members adapted to form a capacity, means responsive to a modulated current for causing a vibration in one of said members, thereby to vary the capacity therebetween at a rate substantially equivalent to the frequency of modulation of said current, a relay circuit having included therein an auxiliary source of current and the capacity formed by said two members, and means for facilitating the flow of leakage current from one of said members to the other. 80
21. In apparatus of the character described, in combination, a pair of spaced conductive members adapted to form a capacity, means responsive to a modulated current for causing a vibration in one of said members, thereby to vary the capacity therebetween at a rate substantially equivalent to the frequency of modulation of said current, a relay circuit having included therein an auxiliary source of current and the capacity formed by said two members, and project- 90
- ing means on one of said members and extending toward the other for facilitating the flow of leakage current from one of said members to the other. 95
22. In apparatus of the character described, in combination, a movable member, a coil mounted to move with said diaphragm, a relatively fixed coil in circuit with said first-mentioned coil, said two coils being adapted when energized by a modulated current to cause relative movement therebetween at a rate substantially commensurate with the frequency of modulation of said current, an auxiliary source of current, means responsive to the movement between said two coils for variably controlling the flow of current from said auxiliary source and at a rate substantially equivalent to the frequency of the relative movement between said two coils, and means for energizing said two coils with energy supplied by the variable flow of current from said auxiliary source. 105
23. In apparatus of the character described, in combination, a movable member, a coil mounted to move with said diaphragm, a relatively fixed coil in circuit with said first-mentioned coil, said two coils being adapted when energized by a modulated current to cause relative movement therebetween at a rate substantially commensurate with the fre- 110
- 115
- 120
- 125
- 130

quency of modulation of said current, a relatively fixed member arranged in spaced relation with respect to said first-mentioned member and adapted to form therewith a capacity, 10
5 an auxiliary source of current having included in the circuit thereof the capacity formed by said two members, whereby the flow of current from said auxiliary source varies at a rate substantially equivalent to

the frequency of relative movement between 10
said two members, and means for energizing said two coils with energy derived from the varying flow of current from said auxiliary source.

In testimony whereof, I have signed my 15
name to this specification this 15th day of
February, 1924.

LUDWIG M. DIETERICH.
